GEORGE E. MOLYNEUX, OF BAYONNE, NEW JERSEY

POWER-TRANSMITTING MECHANISM

Application filed November 28, 1928. Serial No. 322,567.

In the manufacture of coiled filaments for use in incandescent lamps the tungsten wire is coiled in groups of single coils, the groups being separated from one another by uncoiled sections of wire for convenience in securing the ends of each filament, after it has been separated from the adjacent filament, to the terminals. Great care must be exercised in the manufacture of the filaments in order that there shall be no distortion of the filament which might bring adjacent single coils into contact with one another. The mechanism of the present invention has been devised with particular reference to the manufacture of such filaments, although, as will be readily understood, it is capable of use for other specific purposes. In accordance with the invention that part of the mechanism by which, in the specific use described, the wire is fed to the coiling devices (with which the present invention is in nowise concerned) has its movement, normal to the coiling, accelerated at intervals for the purpose of feeding the wire more rapidly. In order that perfect accuracy may be attained it is essential that there shall be no backlash or lost motion or dwell at the time when the acceleration commences or at the time when the acceleration ends. The mechanism which is the subject of the present invention has been so designed as to meet all of the requirements referred to. The part which is to have its movement accelerated at intervals is driven normally, that is, between the intervals of acceleration, by one driver and is driven during each period of acceleration by a driver independent of the first, the two driving mechanisms being so related that the accelerating driver will take hold and let go without any backlash or lost motion or dwell.

The invention will be more fully explained hereinafter with reference to the accompanying drawing in which it is illustrated as embodied in suitable structure and in which:

Figure 1 is a view in sectional elevation on the plane indicated by the broken line 1—1 of Figure 2.

Figure 2 is a view in section on the plane indicated by the broken line 2—2 of Figure 1

looking in the direction of the arrows, and partly broken out.

Figure 3 is a view in section on the plane indicated by the broken line 3—3 of Figure 1 looking in the direction of the arrows.

Figure 4 is a view in section on the plane indicated by the broken line 4—4 of Figure 2 looking in the direction of the arrows.

Figure 5 is a view of a series of groups of coils of wire with stretched out or uncoiled sections of wire between the groups.

In the embodiment of the invention illustrated the part which is primarily to have its movement accelerated at intervals is shown as a drum *a* which is fixed on a shaft *b* by which power is transmitted to an element not shown. The drum may be assumed to be driven at normal speed from a worm gear *c* which is shown as having secured thereto, through their respective hubs, a plate *d* which is mounted loosely on the shaft *b* and has formed thereon an eccentric *d*¹ and is also formed with a limiting notch *d*². Supported upon the plate *d* and coaxial with the shaft *b* and drum *a* is an impeller *e*' which is moved into operative engagement with the drum *a* by the eccentric *d*¹ through the intermediary of balls or rollers *e*¹ interposed between the periphery of the eccentric and the periphery of the circular space in the impeller. The impeller is formed at one end, as at *e*², for driving engagement with an internal shoulder *a*² of the drum *a*. A spring *f*, fixed at one end to the impeller *e* and at the other end to the eccentric plate *d*, tends to keep the impeller on the high part of the cam or eccentric *d*¹, yielding to permit relative movement of the impeller and the eccentric plate. Relative rotary movement of the eccentric plate and the impeller is limited by a pin *e*³ carried by the impeller and entering the notch *d*² of the eccentric plate.

It will be observed that under normal conditions the drum *a* will be driven at a uniform rate by the driver *c* through the impeller *e* and that the driving engagement is such that the drum can be driven at an accelerated rate.

The devices by which the drum *a* is driven at the accelerated rate are in general similar

to the devices at which the drum is driven at the normal rate and may be placed conveniently at the opposite side of the web α^1 of the drum. As shown, there is a plate g mounted loosely on the shaft b and formed with an eccentric g^1 and having secured thereto an accelerating driver h which is shown as a lever and may be actuated at the required intervals by any suitable means. An impeller i also coaxial with the shaft b and drum a is formed for cooperation, through the balls or rollers i^1 , with a cam or eccentric g^1 and is formed as at i^2 for driving engagement with the internal shoulder α^3 of the drum a . The impeller is also provided with a pin i^3 to engage a limiting notch g^2 of the cam plate g . A spring k , connected to the impeller and to the cam plate, tends to keep the impeller on the high part of the cam or eccentric g^1 , yielding to permit relative back movement of the impeller out of engagement with the drum.

It will be seen that when the eccentric plate g is actuated by the accelerating driver h , the impeller i is brought into driving engagement with the drum and the drum is driven at the accelerated rate independently of the normal driving devices.

It will be observed that the two impellers are oppositely placed.

The effect of the mechanism, as applied to the feeding of wire to be coiled, is illustrated in Figure 5, in which a series of groups of coils m are separated by uncoiled or stretched out sections m^1 , so that each group of coils can be separated from the adjacent groups of coils with extensions at each end for convenient attachment to the lamp terminals.

In the operation of the mechanism described the drum a is driven at what is called normal speed from the worm gear c through the impeller e . At intervals the impeller i is actuated by the accelerating driver h and causes movement of the drum at accelerated speed, this action being brief and discontinued. During the action of the accelerating driver the drum moves ahead of the normal speed impeller e and as the action of the accelerating impeller ceases the normal impeller engages the drum and continues its movement at the normal speed.

It will be understood that the invention is independent of the particular use to which it may be applied and that various changes in details of construction and arrangement can be made to suit different conditions of use, the invention not being limited to the particular construction and arrangement shown and described except as pointed out in the claims.

I claim as my invention:

1. A power transmitting mechanism comprising a driven part, a normal driver, an impeller for cooperation with the driven

part, means actuated by the normal driver to effect operative engagement between the impeller and the driven part, a second impeller for cooperation with the driven part, an accelerating driver independent of the normal driver, and means actuated by the accelerating driver to effect operative engagement between the second impeller and the driven part, the impeller being coaxial with the driven part.

2. A power transmitting mechanism comprising a driven part, a normal driver, an impeller for cooperation with the driven part, an eccentric actuated by the normal driver and in operative relation with the impeller to effect operative engagement between the impeller and the driven part, a second impeller for cooperation with the driven part, an accelerating driver, and an eccentric actuated by the accelerating driver and in operative relation with the second impeller to effect operative engagement between the second impeller and the driven part.

3. A power transmitting mechanism comprising a driven part, a normal driver, an impeller for cooperation with the driven part, an eccentric actuated by the normal driver and in operative relation with the impeller to effect operative engagement between the impeller and the driven part, means to permit limited relative rotary movement of the impeller and the eccentric, a spring tending to effect such limited movement, a second impeller for cooperation with the driven part, an accelerating driver, an eccentric actuated by the accelerating driver and in operative relation with the second impeller to effect operative engagement between the second impeller and the driven part, means to permit limited relative movement of the second eccentric and the second impeller, and a spring tending to effect movement of the impeller in one direction.

This specification signed this 27th day of November, A. D. 1928.

GEORGE E. MOLYNEUX.
